UNITED STATES PATENT OFFICE

2,229,322

WHISTLE

Maurice H. Berlin, Chicago, Ill., assignor to Chicago Musical Instrument Co., Chicago, Ill., a corporation of Illinois

Application July 28, 1939, Serial No. 286,963

2 Claims. (Cl. 46—179)

This invention relates to whistles and particularly to a whistle adapted to produce bird calls of various kinds, differing in pitch and tonal quality, and simulating the twittering and vibratory effect of bird calls.

5 In the drawing:

Fig. 1 is a top plan view of a whistle embodying my invention.

Fig. 2 is a vertical, longitudinal sectional view, 10 taken in the plane of the line 2—2 of Fig. 1.

Fig. 3 is a transverse sectional view, taken in the plane of the line 3—3 of Fig. 2.

In that embodiment of the invention shown in the drawing, the elongated hollow tapered body 10 and mouthpiece 11 simulate the body of a bird having a head 12. The mouthpiece 11 is of the fipple type, having an air inlet 13 and an orifice 14 located in the upper wall adjacent the inner end of the inlet 13. A beveled edge 15 is 15 located in the air path near the inner end of the inlet 13. The top 16 is flattened.

The body 10 has one or more tone holes 17 in its top wall and an air outlet 18 at the end of the tone chamber 19 opposite the mouthpiece 20 end. The parts 10 and 11 are provided with interfitting flanges 20 for connecting them together.

A screen 21, preferably of brass wire, extends across the tone chamber 19. The screen may be 30 mounted in the body 10 or inner portion of the mouthpiece in any suitable manner, but the arrangement shown, in which the peripheral edge 22 of the screen disc is engaged between the flanges 20, is preferred. The parts 20 and 21 35 may be cemented together if desired. The screen is located between the mouthpiece inlet 13 and the nearest tone hole 17, and sufficiently removed from the inlet 13 to accommodate a movable ball 23, preferably of cork or the like, 40 between the screen and said air inlet.

By providing a continuous longitudinally ex-

tending air passageway through the instrument body, in which is located a vibrating ball confined by a pervious screen between the mouthpiece and the nearest tone hole, I am able to produce bird calls varying greatly as to pitch and 5 type of sounds.

Changes may be made in details of construction without departing from the scope of my invention.

I claim:

1. A whistle comprising a hollow body forming a tone chamber, a mouthpiece at one end of the body, said body having an air outlet at the opposite end and a tone hole communicating with the tone chamber, the opening and closing of the tone hole serving to vary the pitch of sounds produced in the tone chamber, an air pervious screen extending transversely of the tone chamber between the mouthpiece and said tone hole, and a vibratory member movable in the chamber between the screen and the mouthpiece in the direct path of the air flow for altering the tonal quality of the differently pitched sounds produced in the tone chamber.

2. A whistle comprising a hollow body forming a tone chamber, a mouthpiece having interfitting engagement with the body at one end, said body having an air outlet at the opposite end and a tone hole in its upper wall between said outlet and the mouthpiece, the opening and closing of the tone hole serving to vary the pitch of sounds produced in the tone chamber, an air pervious screen extending across the tone chamber and engaged peripherally by the interfitting parts of the mouthpiece and body, and a member movable in the chamber between the screen and the mouthpiece in the direct path of the air flow for altering the tonal quality of the differently pitched sounds produced in the tone chamber.

40 MAURICE H. BERLIN.
